UNITED STATES PATENT OFFICE.

WILLIAM FISH, OF PLEASANT HILL, OHIO.

WHIP.

SPECIFICATION forming part of Letters Patent No. 319,689, dated June 9, 1885.

Application filed January 2, 1885. (No model.)

To all whom it may concern.

Be it known that I, WILLIAM FISH, of Pleasant Hill, in the county of Miami and State of Ohio, have invented a new and useful Improvement in Combination Whip, which improvement is fully set forth in the following specification and accompanying drawings, in which—

Figure 1 is a perspective view of my improved combination whip; Fig. 2, a perspective view of the device when used as a cane; Fig. 3, a perspective view of the whip, showing the slide on the end; Fig. 4, a perspective view of the semicircular pieces forming the stock; Fig. 5, a perspective view of the clasp-ferrule; Fig. 6, a perspective view of the ferrule with the smaller end of the stock or cane, and Fig. 7 a cross-section of the stock.

The object in the present invention is to provide a device so combined that it may be used either as a whip or cane, as found desirable; and it consists of a cylindrical tapering stock having a slot on one side, and within this piece a whip provided with a thumb-piece sliding longitudinally within a slot, so that the whip may be drawn into the stock out of the way, and thus form a cane, all of which will now be set forth in detail.

In the accompanying drawings, A, Fig. 1, shows a perspective view of my whip. The stock or handle B is formed of two pieces, C and D. (Shown in Fig. 4.) These pieces are formed of metal or other material requisite for the purpose, semicircular and somewhat tapering. These I join together, as shown in Fig. 7, by means of rivet E, so that at the opposite side from the joint a longitudinal slot, F, may be provided. This stock or handle B may be formed of one continuous piece, and the longitudinal slot F cut therein, but for convenience in manufacturing I prefer to form it in sections, as shown. Upon the larger end of this piece B, I provide a ferrule or thimble, G, said thimble G having a cavity to receive stopper when whip is out, and upon the opposite end a smaller ferrule, H, having an opening in the end, is provided. Midway between these ferrules G and H is a clasped ferrule, I, having a slot, J, in one side, to embrace the said piece B, with the slot J corresponding with the slot F. Within this handle or stock B, I provide a section-whip, K, upon the larger

end of which I provide a thumb-piece, L, secured thereto centrally by means of a screw, M, as shown in Fig. 3. The said thumb-piece L is somewhat segmental in form, and designed to slide along the outer circumference of the handle or stock B, while the shank N is designed to extend through the slot F. I design the section-whip K to be somewhat shorter than the stock or handle B, so that by moving the thumb-piece L toward the ferrule G the said whip K may be inclosed within the handle B, so as to form a cane, as shown in Fig. 2. A spring, O, is placed on ferrule G, so that when the thumb-piece L is moved on the ferrule G the said spring will prevent the thumb-piece from returning; and near the ferrule H a similar spring, P, is placed, so that by pressing downwardly upon the spring O and moving the slide L toward the ferrule H the said slide L may be returned in that position. I provide a threaded plug, J', as shown in Figs. 1 and 2, which, when the whip K is drawn out, as shown in Fig. 1, is inserted within the head K' of the ferrule G, so as to close up the end temporarily. When, however, the whip K is drawn into the case, as shown in Fig. 2, the said plug J' is removed from the ferrule G and inserted within the opening at the end of ferrule H, so that the device, as shown in Fig. 2, may be used as a cane without being clogged up with dirt and gravel. When the section-whip K is drawn outwardly, with the thumb-piece L secured in position near the ferrule H, the handle B and section K are designed to form one continuous whip, as shown in Fig. 1; but when the slide L is held in position near the ferrule G by the spring O, and the section-whip K thus drawn into the shell, the device may be used as a cane when stopper is screwed in, as shown in Fig. 2.

I am aware that combined whips and canes have been constructed consisting of a hollow staff adapted to contain a whip, and means for securing the butt-end of the whip to said staff when the whip is in position for use; also, means for inclosing and retaining the whip inside of the staff to adapt the latter to serve as a walking-cane. Such devices I do not broadly claim.

What I claim is—

1. In a combined whip and cane, the combination of a tapered longitudinally-slotted

handle provided with tubular screw-tapped end ferrules and an intermediate slotted clasp, I, in combination with spring catches, a whip, K, and a thumb-slide, L, secured to the butt 5 of the whip, substantially as described.

2. A whip-handle composed of two longitudinal halves united by one edge only, having a slot between the other edges, in combination with the screw-tapered tubular end ferrules, 10 the intermediate slotted clasp-spring catches,

and a whip having a T-shaped slide secured to its butt, substantially as described.

In testimony that I claim the foregoing I have hereunto set my hand this 29th day of November, 1884, in the presence of witnesses.

WILLIAM FISH.
